UNITED STATES PATENT OFFICE.

FRED P. LOVEJOY, OF SPRINGFIELD, VERMONT.

METAL-WORKING TOOL.

1,255,620.

Specification of Letters Patent. Patented Feb. 5, 1918.

Application filed March 28, 1917. Serial No. 158,084.

To all whom it may concern:

Be it known that I, FRED P. LOVEJOY, a citizen of the United States, residing at Springfield, in the county of Windsor and State of Vermont, have invented new and useful Improvements in Metal-Working Tools, of which the following is a specification.

This invention relates to metal-working tools and its object is to provide improved means for fastening a cutter in a holder, to the end that a holder of relatively inexpensive steel may be used to support a cutter of relatively high grade and expensive steel. In all cases where a cutter is secured detachably in a holder it is necessary to secure it so firmly and rigidly with relation to the holder that there will be no "chatter" of the cutter. My present invention is embodied in a structure that causes a tightening of the cutter relatively to the holder in consequence of end-thrust against the cutter by the work, and such tightening effect increases as the end-thrust increases. The tightness of the cutter is not, however, wholly dependent upon end-thrust, for the holder is provided with a set-screw that bears against a shoe to force the latter against the cutter. The shoe and the cutter are provided with coöperative ribs or teeth by which they may be interlocked one with the other, and these teeth, while serving primarily to maintain an adjustment of the cutter relatively to its holder, serve also to transmit end-thrust from the cutter to the shoe. The shoe and the holder are provided with contacting faces arranged to cause a wedging action in consequence of the end-thrust, and such wedging action is transmitted back to the cutter with the tightening effect above mentioned.

Referring to the accompanying drawings:

Figure 1 represents a top plan view of a metal-working tool embodying the present invention.

Fig. 2 is a side elevation thereof, a piece of work being represented by broken lines, and the tool being shown in the act of operating thereon.

Fig. 3 is a side elevation of the cutter.

Fig. 4 is a sectional view through the structure intersected by line 4—4 of Fig. 2. A sectional view of the structure intersected

by line α — α of Fig. 6 would be substantially the same as Fig. 4.

Fig. 5 is a perspective view of the substantially semicylindric locking shoe included in Figs. 2 and 4.

Fig. 6 is a side elevation similar to Fig. 2 showing the invention embodied in a different form.

Fig. 7 is a perspective view of the locking shoe included in Fig. 6.

The same reference characters indicate the same parts wherever they occur.

I have shown two modifications of the invention for the purpose of showing that the latter is capable of being embodied in more than one form, but it is to be understood that the invention is capable of being embodied in other forms than those shown.

In each form the tool comprises a cutter 10, holder 11 therefor, a locking shoe, and a set-screw. In the form shown by Fig. 2 the locking shoe 12 is substantially semicylindric in shape, and I will complete the description of this form before explaining that shown by Figs. 6 and 7.

The holder is provided with a cylindric socket 13 for the cutter, and is provided with a cylindric socket 14 for the locking shoe. These two sockets intersect each other, their axes being substantially at right angles to each other, although not in intersecting relation. The socket 14 is open at one or both ends so that the shoe may be inserted in place or removed by moving it in a direction transverse to the longitudinal lines of the cutter. The cutter is provided with a series of teeth or ribs 15 extending transversely, and the locking shoe is provided with teeth or ribs 16 that are adapted to be interlocked with those of the cutter as shown by Figs. 2 and 4. The teeth of the shoe extend lengthwise of the latter and are parallel to the axes of curvature of the shoe. Since the shoe may be removed axially, it is possible to employ teeth of material depth and also fairly accurately to position the end of the cutter before the shoe is inserted.

The advantage of using a semicylindric shoe is that a cylindric socket such as that indicated at 14 may be formed in the holder with less expense than a socket of any other form, for the reason that a simple boring

operation is all that is required to form the socket. When assembling the tool the cutter is placed in the desired position with regard to endwise adjustment, the teeth 15 thereof being arranged to stand substantially in the middle of the socket 14. The shoe 12 is then moved endwise into the socket 14, and the teeth 16 thereof are thus interlocked with the teeth 15 of the cutter. A set-screw 17 carried by the holder 11 is then screwed down and brought to bear upon the shoe and the latter is thus forced tightly against the cutter. It will be observed that the axis and direction of thrust of the set-screw are at an acute angle in relation to the axis of the cutter, and that such stress tends to force the cutter back to take up any lost motion between the shoe and surface 18 of the holder. The surface 18 and that portion 15 of the shoe that engages it exert a wedging effect upon the cutter that tends to tighten the cutter relatively to the holder. When the tool is being used for turning a piece of work such as that indicated at *a* the end-thrust against the cutter tends to force the latter in the direction indicated by arrow *b*. The end-thrust is transmitted to the shoe by the interlocking teeth 15 and 16, and the shoe is thus brought to bear with additional 20 force against the surface 18 of the holder. The wedging effect hereinbefore mentioned tends to force the cutter in the direction indicated by arrow *c* and the cutter is thus tightened relatively to the holder. 25

30 The wedging action and tightening effect of the shoe may be amplified by providing the shoe and holder with flat faces 20 and 21 respectively as shown by Figs. 6 and 7. The holder shown by Fig. 6 is like that shown by Fig. 2 excepting that the socket for the locking shoe is of another form than cylindric and requires a finishing operation after the socket has been bored. The shoe 12', instead of being semicylindric, is provided with a flat face 22 for coaction with set-screw 17'. While affording greater wedging action and tightening effect the combination shown by Figs. 6 and 7 utilizes the same principles as those explained in conjunction with Fig. 2.

50 In both forms the cutter is cut away diametrically opposite the teeth 15, for the purpose of eliminating contact with the holder at the point indicated at 23 in Fig. 4. In consequence of this formation the cutter is assured of two bearings or separate lines of contact with the holder as indicated at 24, 24, and the effect of this feature is to steady the cutter relatively to the holder by preventing "chattering" in case there should be clearance between the sides of the cutter and the bottom of the cutter were not so cut away and were permitted to bear upon the holder at point 23 the cutter would not be held so 60 confronting faces of the socket therefor. If

securely against rocking from side to side even though the shoe were held tightly against it.

I claim:

1. A metal-working tool comprising a cutter, a holder therefor having a socket for said cutter, said holder having a transverse shoe-receiving socket intersecting said cutter-socket, a shoe arranged in said shoe-receiving socket and removable therefrom in a direction transverse to the cutter, said shoe and said cutter having coöperative interlocking teeth arranged transversely of the cutter to sustain end-thrust of said cutter, and a screw threaded in said holder and arranged to bear on said shoe to force the latter against said cutter. 70

2. A metal-working tool comprising a cutter, a holder therefor having a socket for said cutter, said holder having a transverse shoe-receiving socket intersecting said cutter-socket, a shoe arranged in said shoe-receiving socket and removable therefrom in lines transverse to the cutter, said shoe and said cutter having coöperative interlocking teeth arranged to sustain end-thrust of said cutter, said holder and said shoe having curvilinear coacting surfaces arranged approximately concentric with the axis of the shoe to cause a wedging action and tightening effect upon said cutter in consequence of end-thrust of the latter, and a screw threaded in said holder and arranged to bear upon said shoe to force the latter against said cutter. 80

3. A metal-working tool comprising a cutter, a holder therefor having a socket for said cutter, said holder having a transverse shoe-receiving socket extending from side to side thereof transversely to and intersecting said cutter-socket, a shoe arranged in said shoe-receiving socket and removable from the end thereof, said shoe and said cutter having coöperative interlocking teeth extending longitudinally of the shoe and arranged to sustain end-thrust of said cutter, said holder and said shoe having coacting semi-cylindrical surfaces approximately concentric with the axis of said shoe arranged to cause a wedging action and tightening 100 effect upon said cutter in consequence of end-thrust of the latter, and a screw threaded in said holder and arranged to bear against said shoe to force the latter against said cutter, the axis of said screw and the axis of said cutter being at an acute angle whereby screwing said screw against said shoe will cause end-thrust of said cutter as aforesaid. 105

4. A metal-working tool comprising a cutter, a holder therefor having a socket for said cutter, said cutter and said socket being substantially cylindric, and means arranged to bear against one side of said cutter to force the cutter laterally against the wall of said socket, one of said cylindric elements 110

being cut away through an arc of substantial length opposite said means, to insure two separate lines of contact between said cutter and holder.

5 5. A metal-working tool comprising a cutter, a holder therefor having a socket for said cutter, said cutter and said socket being substantially cylindric, and means arranged to bear against one side of said cutter to

force the cutter laterally against the wall of 10 said socket, said cutter being cut away through an arc of substantial length opposite said means, to insure two separate lines of contact between said cutter and holder.

In testimony whereof I have affixed my 15 signature.

FRED P. LOVEJOY.
